UNITED STATES PATENT OFFICE.

WILHELM FRIEDRICH FRITZ, OF ZURICH, SWITZERLAND, ASSIGNOR OF ONE-HALF TO HENRY ACHILLES ALIOTH, OF BASLE, SWITZERLAND.

MEASURING-FAUCET FOR LIQUEFIED GAS.

SPECIFICATION forming part of Letters Patent No. 643,406, dated February 13, 1900.

Application filed September 28, 1899. Serial No. 781,718. (No model.)

To all whom it may concern:

Be it known that I, WILHELM FRIEDRICH FRITZ, a subject of the King of Würtemberg, residing at Zurich, Switzerland, have invented 5 a new Apparatus for Drawing Off Determined Quantities of Liquid Carbonic Acid or Compressed Gases or Vapors, of which the following is a clear and complete specification.

The present invention has for its object an 10 apparatus for drawing off determined quantities of liquid carbonic acid or of high-pressure gases or vapors from a source of supply into vessels, such as bottles, with reduction of pressure. For this purpose a chamber of 15 fixed capacity is closed in by two valves, which valves by means of a mechanism common to both can be adjusted simultaneously in opposite directions. This chamber in one position of the valves is open toward the source 20 of supply and closed toward the vessel destined or intended to receive the carbonic-acid or other gas or vapor, and in the other position of the valves the chamber is closed toward the source of supply and open toward 25 the said vessel. The change in the position of the valves, however, takes place suddenly and so that the one valve is always closed before the other is opened.

The apparatus may be suitably utilized in 30 the preparation of carbonic beverages—viz., beverages containing carbonic acid.

The accompanying drawing illustrates in vertical section the object of the invention.

The part *a'* of the casing *a* is to be placed 35 in connection with the source of supply, (carbonic-acid bottle,) and the vessel *b*—for instance, a bottle partially filled with water—is to be joined gas-tight to the portion *a²* of the casing. In the casing *a* two valves *c c'*, having 40 gas-tight washers, are arranged coaxially under spring-pressure. The chamber *d*, situated between these two valves *c c'*, possesses a capacity proportionate to the quantity it is desired to draw off. The simultaneous action 45 of the valves is obtained by means of the gearing *e e'* and the eccentric *f f'*, the position of the latter being such that when one—for instance, the lower one—holds open the valve *c'*, belonging to it, the other—for instance, 50 the upper one—closes its valve, and vice versa.

The closing force of the spring is aided by

the pressure of the gas, liquid, or vapor. In the position illustrated of the eccentrics *f f'* and valves *c c'* it is supposed that the connection between the chamber *d* and the source of supply has been closed and that between chamber *d* and the vessel *b* opened. The contents of the chamber discharge into the vessel *b* through the narrow aperture *a³*, which reduces the pressure to the desired amount. 60 After drawing off the contents of the chamber *d* the valves *c c'* are turned by the gearing *e e'* and the eccentrics *f f'* actuated by the crank *g*, so that the connection between the chamber *d* and the source of supply is 65 effected and that between the chamber *d* and the vessel *b* is closed. The chamber now fills afresh with a fixed quantity of gas, liquid, or vapor in order to discharge it into the vessel *b* at the next change of position of the valves, 70 and so on.

The turning of the valves *c c'* from one position into the other is effected suddenly as the eccentrics operate them or release them to the influence of the springs *h h'*. As the 75 closing of each valve always takes place at the beginning and the opening thereof at the end of half a revolution of the eccentrics *f f'*, the one valve is already shut when the other opens, consequently preventing a free current of carbonic acid or the like from passing through the chamber.

Having now particularly described and ascertained the nature of my said invention and in what manner the same is to be performed, 85 I declare that what I claim is—

1. An apparatus for drawing off determined quantities of liquid carbonic acid, compressed gases, and vapors, comprising a casing having an inlet and an outlet, an inlet-valve opening outwardly, an outlet-valve opening inwardly, springs tending to close the respective valves, a chamber of fixed capacity in the casing between said valves, two rotatably-mounted eccentrics for opening the respective valves, said eccentrics being so set as to open the valves alternately and to permit one to close before the other is opened, means for operating both eccentrics simultaneously and means at the outlet for diminishing the pressure of the liquid gas or vapor delivered. 95
2. An apparatus for drawing off determined 100

quantities of liquid carbonic acid, compressed gases, and vapors, comprising a casing having an inlet and an outlet, an inlet-valve opening outwardly, an outlet-valve opening inwardly, springs tending to close the respective valves, a chamber of fixed capacity in the casing between said valves, two rotatably-mounted eccentrics for opening the respective valves, said eccentrics being so set as to open the valves alternately and to permit one to close before the other is opened, means for operating both eccentrics simultaneously and a contracted passage a^3 at the outlet to diminish the pressure of the fluid delivered.

15 3. An apparatus for drawing off determined quantities of fluids, comprising a casing a having an inlet, a contracted outlet a^3 , means for connecting said casing hermetically to the source of supply at the inlet and to the re-

ceiver at the outlet, and a chamber d , of fixed capacity, an inlet-valve c between the inlet and the chamber d and opening outwardly, an outlet-valve c' , between the outlet and the chamber d and opening inwardly, springs tending to close the respective valves, two 25 rotatively-mounted eccentrics f and f' , for operating the respective valves c and c' , and manually-operative gearing connecting said eccentrics and adapted to rotate the same simultaneously.

In witness whereof I have hereunto signed my name, this 14th day of September, 1899, in the presence of two subscribing witnesses.

WILHELM FRIEDRICH FRITZ.
